[57] **CLAIM**

The ornamental design for a combined key holder and self-defense device, as shown and described.

DESCRIPTION

FIG. 1 is a right side elevational view of a combined key holder and self-defense device showing my new design, the environmental structure shown in dotted lines being for illustrative purposes only,

FIG. 2 is a top plan view of the combined key holder and self-defense device, the bottom plan view being a mirror-image thereof,

FIG. 3 is a front elevational view thereof, and

FIG. 4 is a rear elevational view of the combined key holder and self-defense device.
